UNITED STATES PATENT OFFICE.

ALBERT MORITZ, OF NEW YORK, N. Y.

SNAP-HOOK.

SPECIFICATION forming part of Letters Patent No. 596,215, dated December 28, 1897.

Application filed November 11, 1896. Serial No. 611,715. (No model.)

To all whom it may concern:

Be it known that I, ALBERT MORITZ, a citizen of the United States, residing in the city, county, and State of New York, have invented 5 an Improvement in Snap-Hooks, of which the following is a specification.

This invention relates to snap-hooks.

The object of the invention is to provide a safe durable hook simple and convenient in 10 operation and construction and capable of withstanding rough treatment without getting out of order; and the invention consists of the construction hereinafter set forth.

In the drawings forming part of this specification, and in which like letters of reference 15 designate corresponding parts, Figure 1 is a side elevation of a hook embodying the invention; and Fig. 2 is a side elevation of the same taken at a right angle to Fig. 1.

20 A is the body portion of the hook, preferably made in **C** shape and consisting of the long limb or shank c, curved to form a hook. This **C**-shaped body portion generally has a short limb b. In the best form of the invention the body portion is made in one piece. 25 It is provided with an eye a or its equivalent for the purpose of connecting the hook with a cable, cord, or the like, and this eye is preferably formed in one piece with the body portion A. The eye is shown as standing in the same plane as the limbs b and c, but it may of course be disposed at any angle to this plane. The upturned end of the limb c is generally formed with a bevel c', and this 30 limb c terminates with a projecting lip d. Pivoted or hinged to the end of the limb b is a safety latch or tongue B, whose free end meets the upturned end of the limb c and is arranged to swing inward, so as to permit the 35 hook to fully engage the object with which it is to be connected; but the latch is rendered by suitable means incapable of swinging outward beyond the end of the limb c, so as to prevent accidental disengagement of the hook.

40 Various means may be employed to prevent the latch or tongue B from swinging outward beyond the end of the limb c. In the best form of the invention now known to me 45 this is accomplished by causing the upturned end of the limb c to act as a stop for the latch, and in providing for this arrangement

I preferably bevel the contacting end of the latch B at e and the limb c at c', as shown in Fig. 1. The lip d projects outward and serves 55 as a catch to enable the hook to be brought into easy engagement with a bucket-handle, ring, or other object with which the hook is to be connected. For example, suppose the hook were to be connected with a ring. The 60 attendant only engages the lip d with the ring, when by a little pressure the ring will slide along the lip and force back the latch B and enter the hook, the latch returning then to its place. Thus it is not necessary for the attendant to open the latch by hand.

C is a leaf-spring having its end secured between the latch or tongue B and the limb or shank c on the inner sides. It has one end secured by rivets e, or is otherwise suitably 70 attached to the limb c to prevent displacement, and its other end engages with the latch or tongue B in a notch f, so as to press against the tongue to hold it normally closed. The spring is out of contact with the limb c and 75 tongue B, except at its ends, thereby securing freedom of action for the spring when the tongue is pressed open. It will be seen that the arrangement and location of the spring amply protects it from injury such as would 80 result from ordinary wear and that the spring is not liable to become displaced. The tongue B is able to open quite wide and at the same time the strain on the spring is distributed throughout its length, thus preventing wear 85 and strain on the spring at one point and liability to fracture. In its best form the spring is made of a flat strip of metal and is normally bent between its ends. Of course both ends of the spring might be riveted or 90 permanently attached to the limb c and tongue B, or either end might be alone riveted in place or otherwise suitably secured. As shown in the drawings, the lip d extends upward as well as outward, thus being formed 95 with a bevel d'. The bevel d' of the lip is generally made continuous with the bevel c' of the limb c. This is the preferred form of the lip.

What I claim as new, and desire to secure 100 by Letters Patent, is—

1. A snap-hook having a **C**-shaped body, the lower limb c of which terminates in an outwardly-projecting beveled lip, combined with

an inwardly-opening tongue pivoted to the upper part of the body and a leaf-spring secured to the inside of the body and engaging by its free end only the tongue, substantially 5 as described.

- 5 2. In a snap-hook, the combination of the C-shaped body portion comprising the short limb *b* and long curved limb *c*, an inwardly-opening tongue *B* pivoted to the limb *b* and meeting the upturned end of the limb *c*, and a bent leaf-spring engaging at its end only the tongue *B* and limb *c* and located between them, substantially as set forth.
- 10 3. In a snap-hook, the combination of the C-shaped body portion comprising the short limb *b* and long curved limb *c*, an inwardly-opening tongue *B* pivoted to the limb *b* and meeting the upturned end of the limb *c*, and a bent leaf-spring engaging at its end only the tongue *B* and limb *c* and located between them, substantially as set forth.

- 15 3. In a snap-hook, the combination of the C-shaped body portion comprising the short limb *b* and long curved limb *c*, an inwardly-opening tongue *B* pivoted to the limb *b* and meeting the upturned end of the limb *c*, and a bent leaf-spring engaging at its end only the tongue *B* and limb *c* and located between them, substantially as set forth.

limb *b* and long curved limb *c* having a beveled lip *d*, an inwardly-opening tongue *B* pivoted to the limb *b* and meeting the upturned end of the limb *c*, and a bent leaf-spring engaging at its end only the tongue *B* and limb *c* and located between them, substantially as set forth.

In testimony whereof I have signed my name to this specification in the presence of two subscribing witnesses.

ALBERT MORITZ.
